US0D1109660S

(12) United States Design Patent (10) Patent No.: US D1,109,660 S
(45) Date of Patent:  Jan. 20, 2026

(54) FLOOR MAT ASSEMBLY

(71) Applicant: Volvo Truck Corporation, Gothenburg (SE)

(72) Inventors: Phillip Ma, Morrisville, NC (US); Christian Johan Christensen Del Rello, Winston-Salem, NC (US); Jason Dabel, Greensboro, NC (US)

(73) Assignee: Volvo Truck Corporation, Gothenburg (SE)

() Term: 15 Years

(21) Appl. No.: 29/985,893

(22) Filed: Jan. 17, 2025

(51) LOC (15) Cl. 12-16

(52) U.S. Cl.

USPC D12/203
